(57) **CLAIM**

We claim the ornamental design for a wagon robot, as shown and described.

DESCRIPTION

FIG. 1 is a front perspective view of a wagon robot of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a front perspective view thereof shown in a first alternate position;

FIG. 9 is a front perspective view thereof shown in a second alternate position;

FIG. 10 is a front perspective view thereof shown in a third alternate position;

FIG. 11 is a front perspective view thereof shown in a fourth alternate position; and,

FIG. 12 is a front perspective view thereof shown in a fifth alternate position.

The broken line showing of wagon robot is included for the purpose of illustrating environment and forms no part of the claimed design.
